Primary Examiner—Martie K. Holtje*Attorney, Agent, or Firm*—McCarter & English, LLP; Allen N. Friedman[57] **CLAIM**

I claim a whiteboard with integrated marker storage, as shown and described.

DESCRIPTION

FIG. 1 is a perspective view of a whiteboard with integrated marker storage showing my new design, the two writing instruments depicted by means of broken lines being shown for illustrative purposes only and forming no part of the claimed design;

FIG. 2 is a front elevational view;

FIG. 3 is a bottom plan view; and,

FIG. 4 is a right side elevational view, the left side being a mirror image thereof.

The rear of the article is unornamented.
